UNITED STATES PATENT OFFICE.

LESTER L. LADD, OF LOCKPORT, ILLINOIS, ASSIGNOR TO PHOTOMETRIC PRODUCTS CORPORATION, OF CHICAGO, ILLINOIS, A CORPORATION OF DELAWARE.

SELECTING DEVICE.

Application filed October 17, 1921. Serial No. 508,411.

This invention relates to selective control devices, and more particularly to a device wherein any desired mechanism may be selectively controlled by the position of a swinging needle or arm, and is an improvement on the device shown in my application Serial No. 422,561, filed November 8, 1920.

The invention further relates to a device wherein any desired mechanism may be selectively controlled by the position of an indicating needle, adapted to assume various positions in accordance with the variations of an electric current, the variations of the current being in accordance with the characteristics of the objects to be acted on by the mechanism controlled by said device.

It is a purpose of the invention to provide a control device, having a plurality of oppositely arranged contacts and a movable member that is adapted to bridge the gap between any pair of said contacts to complete a circuit to operate any desired mechanism in accordance with the selection of said control device, the selection being in accordance with the position of said movable member.

It is a further purpose of the invention to provide a control device having a plurality of oppositely arranged contacts and a swinging needle carrying a member operating between said contacts adapted to bridge the gap between them to complete a circuit to operate any desired devices in accordance with the selection of the control device, dependent upon the position of said needle under the influence of the variations of a variable electric current. It is a still further purpose of the invention to provide a device of the above mentioned character wherein both of said sets of contacts are movable toward each other, and wherein the needle loosely supports a contact member that is adapted to be pinched or clamped between said movable contacts to complete a circuit to operate certain devices in accordance with the selection of said control device as indicated by said needle.

It is also an object of the invention to provide a selective control device having oppositely arranged sets of contacts, the number of contacts of one set being a multiple of the number of contacts of the other set, whereby the number of selections of the device is mul-

tiplied without unnecessary multiplication of the operating devices of the mechanism controlled by said control device.

It is a further object of the invention to provide stop members at the opposite ends of one of said sets of contacts to limit the movement of said needle, said stop members serving as contacts to be operated due to the effect on the needle of all objects out of the range of said selecting mechanism.

It is also an object of the invention to provide a single spring means for moving said contacts toward each other so as to yieldingly grip the contact on the swinging needle between them and to provide adjusting means for said contacts.

It is a further object of the invention to provide means for adjusting the needle so that the pivot thereof will be at such a point that the contact member carried thereby will be at the center of the space between the faces of the contacts between which said contact member operates.

Other objects and advantages of the invention will appear as the description of the accompanying drawings, showing one form that my invention may take, proceeds. However, I desire to have it distinctly understood that I do not intend to limit myself to the exact details of structure shown in the accompanying drawings or described in the specification but desire to include as part of my invention all such obvious modifications and changes in structure as would occur to a person skilled in this art and as would fall within the scope of the claims.

In the drawings:

Fig. 1 is a plan view of the selector embodied in the present invention;

Fig. 2 is a section thereof taken on the line 2—2 of Fig. 1;

Fig. 3 is a section taken on line 3—3 of Fig. 1;

Fig. 4 is a section taken on the line 4—4 of Fig. 1; and

Fig. 5 is a circuit diagram showing the arrangement of the contacts and electromagnets operated by said selector.

Referring in detail to the drawings, the improved selector comprises a casing 10 having the end members 11 and the side members 12, one of the end members 11 being provided with an extension 13 having a

yoke-like portion 14 and both said end members 11 being provided with bosses 15 and with openings 16 through which extend guide rods 17.

- 5 The bottom of the casing 10 is provided with an upstanding ear 18 at each side thereof. Each of the ears 18 is provided with an opening forming a bearing for the pivot member 19 of the bell crank lever 20, said bell crank lever having an arm 21 extending upwardly from the same and terminating in a U-shaped member 22 which serves as a bearing for the stub shaft 23 provided on the block 24, there being two of said stub shafts, one extending laterally from each end of the block 24, the block 24 being mounted slidably on the rods 17. The other arm 25 of the bell crank lever has pivotally secured thereto at 26 the link 27 which link 27 is pivotally mounted at 28 on the member 29 which extends from one rod 17 to the other rod 17 and is mounted on the rods so as to move therewith, being secured thereto by means of pins 30 or in any other suitable manner.
- 25 Mounted on the member 29 is a plurality of contacts 31. The member 29 is also provided with a pair of end contacts 32, said contacts 32 being provided with projections 33 which act as stops for the needle 34 of the indicating instrument 35 operated by means of the coil 36, the needle of said indicating instrument being mounted to turn with the shaft 37 mounted in bearings 38 on the bracket 39 and the plate 40 respectively.
- 35 The needle 34 is provided with a hook-like member 41 at the end thereof which carries a contact member 42. It will be seen from the above that the needle 34 will swing about the axis of the pivots at 37 as a center so that the contacts 42 will swing in an arc, the center of curvature of which is at the pivot point 37.
- The block 24 is provided with a plurality of contacts arranged in sets of five, said contacts being numbered 43, 44, 45, 46 and 47 respectively. All of the contacts 43 are connected together by means of the connector 48 which is electrically connected with the wire 49 which leads out of the instrument; similarly, all of the contacts 44 are connected with the connector 50 which is in turn connected with the wire 51; all of the contacts 45 are electrically connected by means of the connector 52 which is connected with the wire 53 leading out of the instrument; all of the contacts 46 are connected by means of the connector 54 which is electrically connected with the wire 55 which leads out of the instrument; and all of the contacts 46 are connected by means of the connector 56 which is electrically connected with the wire 57 which also leads out of the instrument.

The wires 49, 51, 53, 55 and 57 pass through the yoke 58 of insulating material secured to the block 24. Each of the con-

tacts is insulated from each other by suitable insulating material and end contact members 59 and 59' are provided opposite the contacts 32, said end contacts being cut away at 60 to receive the projections 33.

The opposing faces of the contacts 31 and 32 and the contacts 59', 43, 44, 45, 46, 47 and 59 are curved on the arc of a circle so that they will interfit, the contacts 31 and 32 being convexly curved as shown at 61 and the co-operating contacts being concavely curved as shown at 62. Operating in the space 63 between said contacts is the contact member 42 on the end of the needle 34. In order to prevent the contact member carried by the end of the needle from engaging with the contacts on the opposite sides thereof which would prevent the needle from swinging, an adjustment is provided for the indicating instrument so as to adjust the pivots 37 thereof so as to provide for the swinging of the needle freely between the contacts. The member 40 is provided with laterally projecting tongues 64 which are adapted to slide in the grooves 65 provided in the member 10, the member 10 being provided with a removable plate 66 forming one wall of the groove so as to provide for the removal of the plate 40 carrying the indicating instrument, when desired.

The plate 40 is provided with a rearwardly extending arm 67 having a forwardly extending portion 68 with a bore 69 therein to receive the restricted portion 70 of the screw 71 which is screwthreadedly received in the internally screwthreaded boss 72 on the member 11 and which is provided with a knurled head 73 for turning the same.

It will be seen that as the knurled head 73 is turned, the arm 67 will be moved inwardly or outwardly depending upon the direction of rotation of the head of the screw, thus moving the slideable member 40 longitudinally of the casing 10 so as to adjust the position of the pivot 37. The casing is provided with a glass cover 74 to close the same. The members 17 extend beyond the casing and are threaded at the ends at 75 and are provided with nuts 76 engaging said threads.

Mounted on the rods 17 and operating between the nuts 76 and the bosses 15 is the cross bar or yoke 77 having a laterally deflected portion 78. The end member 11 is provided with a central boss 79 and an opening 80 through which extends the rod 81 serving as a guide member for the member 77, said member being provided with an opening 82 to receive said rod 81. Coiled about the rod 81 is a spring 83, said spring 83 bearing against the boss 84 on the member 11 and against the deflected portion 78 of the yoke 77. The rod or shaft 81 is provided with a forked or bifurcated portion at the end thereof having the arms 85 between which is journaled the roller 86.

The yoke-like member 14 is provided with a vertical screwthreaded opening 87 which is adapted to receive the screw 88 provided with a restricted portion 89 and with an enlargement 90 so as to provide shoulders on both sides of the block 91 mounted on said screw so that as the screw 88 is turned either into or out of the opening 87, the block 91 will be moved down or up depending upon 10 the direction in which the screw is turned.

The end of the yoke 14 is provided with an enlargement at 92 which screwthreadedly receives the screwthreaded sleeve 93 having the hexagonal head portion 94 with which 15 the block 91 is adapted to engage when the same is screwed down. The member 93 acts as a stop to limit the movement of the yoke 77. The yoke 77 is moved outwardly or 20 away from the casing by the action of the spring 83 and as the yoke bears against the nuts 76, the rods 17 are carried with the yoke and the member 29 is carried with the rods so as to swing the links 27 and bell 25 crank lever 20 in such a direction that the block 24 approaches the block 29 and the contacts that are opposite each other will approach each other.

It will thus be seen that by adjusting the position of the member 93, the distance 30 which the contacts will travel toward each other will be adjusted thereby.

In order to separate the contacts, the rod 82 has the roller 86 on the end thereof engaging with a cam 95 having a raised portion 96 and a depressed portion 97 and when the roller 86 engages with the raised portion 96, the spring will be compressed and the parts will be in the position shown in the drawings with the contacts separated so 40 that the needle can carry the movable contact 42 along between the same. However, when the low portion of the cam 97 is in engagement with the roller 86, then the spring will be allowed to act to bring the contacts 45 toward each other and clamp the movable contact 42 therebetween to complete the circuit between the contacts.

The projections 33 act as stops to limit the movement of the movable contact member as the same cannot swing past the projections 33. The wires from the contacts extend downwardly into the casing and pass out through the opening 98 provided in the bottom of the casing 10, one of the wires 53 being shown as passing through the same from one set of contacts and a wire 99 from the other set of contacts being shown as passing through said opening 98. The needle 34 is provided with a rearward extension 100 that is adapted to engage with the stop members 101 and 102 to limit the movement of the needle, said members being so placed that the needle will engage with said stops at the same time that it engages with the 65 stop members 33.

Referring now to Fig. 5 in which figure are shown the end contacts 31 of the series of contacts 31, the contacts cooperating with said contacts 31 and the end contacts 59 and 59', and the stop members cooperating therewith; in said figure the line wires 103 and 104 are shown with the wire 103 having the wires 99 and 99' leading therefrom to the contacts 31. The wire 99 has an electromagnet 105 in series therewith while the wire 75 99' has no such electromagnet.

For the sake of convenience, in Fig. 5 the member cooperating with the member 59' is designated 32' and the member cooperating with the member 59 is designated 32. Opposite the contacts 31 are sets of contacts, any number of said contacts being usable in a set but five being used in the present construction, said contacts being numbered 43, 44, 45, 46, and 47, as described in connection 85 with the other figures of the drawings.

As previously described, the contact members 43 are connected by the wire 48; the contact members 44 are connected by means of the wire 50; the contact members 45 are 90 connected by means of the wire 53; the contact members 46 are connected by the wire 54; and the contact members 47 are connected by means of the wire 56. The wire 48 also connects the contact 59' with the contacts 43 and the contacts 59 and 59' are connected by means of the connector 106. Thus the contact 59 is also connected with the contacts 43 electrically. The members 32 and 32' are connected by the connector 107 100 and the member 32' is connected with the adjoining contact 31 by the connecting member 108; thus the contacts 32 and 32' and one of the end contacts 31 are electrically connected. From the lead 104 extends the wire 109 which has a switch 110 interposed in the length thereof. The connector 48 is connected with the wire 109 by means of the wire 49; the connector 50 is connected with the wire 109 by means of the wire 51 which 110 has the electromagnet 110 in series therewith; the wire 53 which connects the connector 52 with the wire 109 has the electromagnet 111 in series therewith; the wire 55 which connects the connecting member 54 115 with the wire 109 has the electromagnet 112 in series therewith; and the wire 57 which connects the member 56 with the wire 109 has the electromagnet 113 in series therewith.

The present invention is adapted for use 120 in selectively controlled mechanism of various sorts and is particularly adapted for use with a sorting machine such as that described in my co-pending application, Serial No. 508,410; filed Oct. 17, 1921. The selector is particularly adapted for making a large number of selections with a minimum number of mechanical parts. In order to do this, the selector is so constructed and the mechanism operating therewith must be so 125 130

operated that the operations performed by the mechanism through the aid of the electromagnets 110, 111, 112 and 113, is done in two parts or steps.

- 5 In the above mentioned application a machine is shown that is provided with a hopper for receiving articles to be sorted from which the articles are carried into the range of a photoelectric cell, which photoelectric cell is effected by the color of the articles so as to produce a current strength dependent upon the color. The current produced by the photoelectric cell is very small as is well known, and this is amplified by the use of a 10 thermionic amplifier, commonly known as an audion, in the usual manner. The amplified current is the current that is passed through the indicating instrument shown in the present application, and as the various 15 contacts are made, two sets of devices are operated to cause the carrier upon which the article is supported to dump the article at a station in accordance with the position of the needle of the instrument. By the use of 20 two different devices the action of one of the devices is multiplied so as to reduce the number of parts necessary to obtain a large 25 number of selections. In the form shown in the above mentioned application this is accomplished by providing a removable support at various points along the route of travel of the carriers, the support being selectively removed in accordance with the position of the needle of the indicating 30 instrument and the direction of discharge of the article is controlled to multiply the 35 selections by means of a switching mechanism which guides a projection on the carrier into any one of a plurality of annular 40 tracks to vary the angularity of the carrier relative to the radial position. This is more fully described in my application, Serial No. 508,410, referred to above, and is only gone into briefly here in order to convey an idea 45 of the general application of the device shown in the present application, and it will be obvious that the same can be used for selecting articles in other ways than that referred to above without departing from 50 the invention.

In the device shown the number of different selections is twenty-nine, there being thirty different combinations of contacts possible but one of these is used to discharge articles not desired from the machine in the case of the sorting machine and could be used for any other purpose desired in any other device to which the selector can be adapted.

- 60 In order to obtain the thirty different combinations of contacts, the small contacts are arranged in six sets of five each and the contacts 31 are arranged so that each contact 31 is opposite a set of five of said smaller contacts. In order to reduce the number of

electrically operated parts through the electromagnets, there is one positive mechanically operated mechanism provided to correspond with the contacts controlling the wires 49 and 99' which are not provided 70 with electromagnets.

It will be noted that when the movable contact 42 is opposite the contact 31 connected with the wire 99' and opposite the contact 47 as shown in Fig. 5, the electromagnet 113 will operate to operate mechanism controlled thereby and the mechanically operated mechanism will operate due to the fact that the current is passing through the wire 99' in conjunction with said mechanism controlled by the magnet 113, while when the contact member 42 is opposite the contact member 46, the mechanism controlled by the magnet 112 will operate in conjunction with the mechanism that is 80 so placed in operation by mechanical means and similarly the mechanism controlled by the electromagnets 111 and 110 will be operated thereby when the movable contact is opposite the contacts 45 and 44 85 respectively, said mechanism operating, of course, in conjunction with the mechanically controlled mechanism which operates when the current passes through the member 99'. When the contact 42 is opposite the contact 90 43 and said contact 31, then the mechanism set in operation by said mechanical means will be thrown in operation and will operate in conjunction with means thrown into operation mechanically, due to the fact that the 95 current is passing through the wire 49 which has no electromagnet operating in conjunction therewith. Although the device operated when the current is passing through the wires 99' and 49 is positively operated it is 100 so arranged that it will not operate until after the possibility of any of the other devices operating on the mechanism is passed. When the movable contact 42 is opposite 105 one of the said contacts 44, 45, 46, or 47 and one of the contacts 31 connected with the wire 99, the electromagnet 105 in series with said wire will set certain mechanism in operation which will operate in conjunction with the mechanism controlled by the particular 110 magnet 110, 111, 112 or 113 which is connected with said contacts through the wires as previously described, while if the movable contact is opposite the contact 43 and said member 31, then the electromagnet 105 115 will operate in conjunction with the mechanical means for controlling certain mechanisms in operation which operates positively and is controlled by the wire 49.

The contacts 32 and 32' are provided with 120 stops 33 for limiting the movement of the member 42 and said contacts are connected with each other as previously described by means of the wire 107 while the cooperating contacts 59 and 59' are connected by means 125 130

of the wire 106 and said contacts are respectively connected with the one end contact 31 by means of the conductor 108 and with the contacts 43 by means of the conductor 48 so that when the member 42 reaches the limit of its movement in either direction, the same mechanism will be operated as would be operated if the movable contact member were opposite the last member 31 that is provided with an operating magnet 105 and opposite the contact 43 associated therewith, thus providing a means for discharging articles from a machine that are not within the range of the selections 15 when said mechanism is used for sorting as described in said co-pending application mentioned above. It is to be noted that the mechanism operated by the devices is arranged in such a manner that the operations 20 would take place successively, depending on the position of the contact 42, from right to left in Fig. 5, that is, the first possible operation by the device controlled by the selecting means is that controlled by the contact 31 25 at the right end of the instrument and the member 43, and this also is the operation which eliminates from the machine all articles out of the range of the machine, due to the operation of the stops and contacts 32, 30 31', 59 and 59'. The last position of the contact 42 that operates the mechanism is opposite the contact 47 which cooperates with the contact 31 at the opposite end of the series or that contact in series with the 35 wire 99'.

It will thus be seen that a series of selections is made in accordance with the position of the indicating member, said selections being made in two steps, one step of which is

40 dependent upon the contact 31 opposite which the movable contact 42 is located, and the other of which is dependent upon the contact member 43, 44, 45, 46 or 47 opposite which the movable contact 42 is located.

45 It will also be seen that a positive means is provided for discharging articles from the mechanism that are out of the range of the selections of the device, by the provision of the stop members and cooperating contacts associated with said stop members.

It will also be noted in connection with the mechanical features of the selector that by providing the adjustment for the bearings of the needle, all possibility of the 55 needle sticking because of the same not being properly aligned, between the contacts will be avoided and that due to the fact that the contacts are positively separated by means of a cam and are brought together only by 60 means of a spring device, the tension of which is adjustable, there will be no injury done to the movable contact 42 or the faces of the positively arranged contacts, due to the contacts moving into engagement.

65 Having thus described my invention, what

I desire to claim and secure by U. S. Letters Patent is:

1. A device of the character described comprising two sets of oppositely arranged individual contacts, and a contact member 70 mounted for movement between the opposing faces of said contacts, both of said sets of contacts being movably mounted and means for moving said sets toward and away from each other. 75

2. A device of the character described comprising two sets of oppositely arranged contacts arranged in rows, and a contact member mounted for movement between the opposing faces of said contacts along said rows, 80 both of said sets of contacts being movably mounted, means for moving said sets away from each other, and means for urging said sets of contacts toward each other.

3. A device of the character described comprising two sets of oppositely arranged contacts arranged in rows, and a contact member mounted for movement between the opposing faces of said contacts along said rows, 85 both of said sets of contacts being movably mounted, means for moving said sets away from each other, and resilient means for urging said sets of contacts toward each other. 90

4. A device of the character described comprising two sets of oppositely arranged contacts, the opposed faces of said contacts being curved and parallel so as to provide a uniform space therebetween, a contact member mounted to move between said contacts in a curved path and means for adjusting said movable contact member. 100

5. A device of the character described comprising two sets of oppositely arranged contacts, the opposed faces of said contacts being curved and parallel so as to provide a uniform space therebetween, a contact member mounted to move between said contacts in a curved path and means for adjusting said movable contact member transversely of said space. 110

6. A device of the character described comprising two sets of oppositely arranged contacts, the opposed faces of said contacts being curved and parallel so as to provide a uniform space therebetween, a contact member mounted on an arm, a pivot member about which said arm turns, and means for adjusting said pivot so that said contact member will move freely between said contacts. 115

7. A device of the character described comprising sets of oppositely arranged contacts, said contacts being movable toward and away from each other, and having the opposed faces thereof curved and parallel so as to provide a space of substantially uniform width therebetween when said contacts are separated, a needle mounted to swing about a pivot member, a contact member mounted on said needle, and means for ad- 120

125

justing the pivot of said needle to so position the contact member mounted thereon as to provide for the free swinging thereof between said sets of contacts when the same are separated.

8. A device of the character described comprising a base member, oppositely arranged sets of contacts movably mounted relative to said base member, a needle supporting member adjustably mounted on said base member, and a swinging needle mounted on said supporting member to move between said sets of contacts.

10. A device of the character described comprising a base member, oppositely arranged sets of contacts movably mounted relative to said base member, a needle supporting member slidably mounted on said base member, means for adjusting said member relative to said base, and a needle mounted on said supporting member to swing in a plane and having a member thereon movable relative thereto and moving between said sets of contacts.

15. A device of the character described comprising a base member, oppositely arranged sets of contacts movably mounted relative to said base member, a needle supporting member, a swinging needle movable between said sets of contacts, cooperating guide members on said base member and said needle supporting member, and means for moving said needle supporting member along said guides to adjust the position of said needle.

20. A device of the character described comprising a base member, oppositely arranged sets of contacts movably mounted relative to said base member, a needle supporting member, a swinging needle movable between said sets of contacts cooperating guide members on said base member and said needle supporting member, and an adjusting screw for moving said needle supporting member along said guides to adjust the position of the pivot of said needle.

25. A device of the character described comprising oppositely arranged sets of contacts the contacts of each set comprising a progressively arranged series of contacts, and a contact member mounted to move between said sets of contacts to complete the circuit between opposite contacts, the end contacts of one of said sets being provided with stop members to limit the movement of said movable contact member opposite the end contacts of said sets, said end contacts being connected with the contacts of said series adjacent one end contact of each set.

30. A device of the character described comprising oppositely arranged sets of contacts the contacts of each set comprising a progressively arranged series of contacts, means for moving said sets of contacts toward and away from each other, stops on

the end contacts of one of said sets and a movable contact member adapted to complete the circuit between opposite contacts and engaging said stops to limit the movement thereof opposite the end contacts of said sets, the end contacts of each set being connected with each other and with a contact of said series.

35. In a device of the character described, oppositely arranged sets of contacts the contacts of each set comprising a progressively arranged series of contacts, a contact making member movable between said sets of contacts and adapted to cooperate therewith, means for moving said contact making member into position in accordance with the fluctuations of an electric current and stops for limiting the movement of said contact making member opposite the end contacts of said sets, the end contacts of each set being connected in parallel.

40. In a device of the character described, a support provided with guide members, rods mounted for movement in said guide members, oppositely arranged sets of contacts mounted on said rods, one of said sets of contacts being mounted to move with said rods and the other of said sets of contacts being movable on said rods, means for moving said rods and a connection between said sets of contacts, whereby said contacts are moved in opposite directions upon movement of said rods.

45. In a device of the character described, a support provided with guide members, rods mounted for movement in said guide members, oppositely arranged sets of contacts mounted on said rods, one of said sets of contacts being mounted to move with said rods and the other of said sets of contacts being movable on said rods, a spring for moving said rods in one direction, means for moving said rods in the opposite direction against the action of said spring, and a connection between said sets of contacts, whereby said contacts are moved in opposite directions upon movement of said rods.

50. In a device of the character described, a support provided with guide members, rods mounted for movement in said guide members, oppositely arranged sets of contacts mounted on said rods, one of said sets of contacts being mounted to move with said rods and the other of said sets of contacts being movable on said rods, means for moving said rods and a connection between said sets of contacts comprising a bell crank lever, whereby said contacts are moved in opposite directions upon movement of said rods.

55. In a device of the character described, a support provided with guide members, rods mounted for movement in said guide members, oppositely arranged sets of contacts mounted on said rods, one of said sets of contacts being mounted to move with said rods

rods and the other of said sets of contacts being movable on said rods, means for moving said rods and a connection between said sets of contacts comprising a bell crank lever having its pivot mounted on said support and having a pivotal connection with one of said sets of contacts and being connected through a pivoted link to the other of said sets of contacts, whereby said contacts are moved in opposite directions upon movement of said rods.

19. A selective control device comprising an arm mounted to swing about a pivot, means for swinging said arm, a contact making member loosely mounted on said arm, oppositely arranged sets of contacts, said sets of contacts being movable toward each other to clamp said contact member between the same, and a plurality of operating circuits connected with said contacts, said contact making member operating along said sets of contacts and between the same.

20. A selective control device comprising

oppositely arranged rows of contacts, a pivoted arm, means for moving said arm about its pivot, a contact making member suspended between said contacts from said arm and movable along said rows as said arm swings on its pivot, and means for moving said rows of contacts toward each other to clamp said contact member between certain of said contacts.

21. A selective control device comprising oppositely arranged rows of contacts, a pivoted arm, means for moving said arm about its pivot, a contact making member freely suspended between said contacts from said arm and movable along said rows as said arm swings on its pivot, and means for moving said rows of contacts toward each other to clamp said contact member between certain of said contacts.

In witness whereof, I hereunto subscribe my name this 19th day of September, A. D. 1921.

LESTER L. LADD.
